J. J. PEMBERTON, OF OAKLAND, ILLINOIS.

Letters Patent No. 92,999, dated July 27, 1869.

VENTILATOR FOR CHIMNEYS

The Schedule referred to in these Letters Patent and making part of the same.

To all whom it may concern:

Be it known that I, J. J. PEMBERTON, of Oakland, in the county of Coles, and State of Illinois, have invented a new and useful Improvement in Ventilating Chimneys; and I do hereby declare that the following is a full, clear, and exact description thereof, which will enable others skilled in the art to make and use the same, reference being had to the accompanying drawing, forming part of this specification.

The object of this invention is to provide an improved means for ventilating chimneys of fire-places, grates, &c., by the admission of the external atmosphere thereto, to facilitate the draught, to prevent smoking, also to facilitate combustion, and to prevent the cold air from rushing in through door, window, and other cracks, chilling the room, all as hereinafter more fully specified.

Figure 1 represents a fire-place provided with my improved ventilating-apparatus.

Figure 2 represents a transverse sectional elevation of the same, taken in the line $z z$ of fig. 1.

Figure 3 represents a plan view of the top part of a ventilating-arch for chimneys.

Similar letters of reference indicate corresponding parts.

I propose to form the arch for supporting the brick above the fire-place of perforated metallic tubes A, either of cast or wrought-metal, and in any preferred form, whether arched, flat, or otherwise, to be supported by vertical tubes B, placed in the jambs, and connected at the base with pipes communicating with the external atmosphere.

These ventilators may serve to form, also, ornamental fronts to the fire-places or grates, and may be placed therein in the construction of the chimneys, or they may be arranged to be afterward put in place.

The air is delivered through the perforations at the upper part A of the arches, and, if preferred, the vertical part B may also be perforated.

Having thus described my invention, What I claim as new, and desire to secure by Letters Patent, is—

Metallic ventilating-arches A, B, constructed and arranged for application to the chimneys, substantially as specified.

J. J. PEMBERTON.
